UNITED STATES PATENT OFFICE.

JOHN D. BROWN, OF BRECKENRIDGE, TEXAS.

COUNTERBALANCED PUMPING JACK.

Application filed March 29, 1924. Serial No. 702,824.

This invention relates to improvements in pumping apparatus.

The primary object of this invention is the provision of an improved pumping jack 5 for use in connection with oil pumping apparatus, embodying an improved counterbalancing feature, and means to permit its collapsing into an out of the way relation with respect to a pumping rod.

10 A further object of this invention is the provision of a pumping jack which includes counterbalancing means to offset the excessive weight of the pump line and to permit operation of the pump line or rod with the 15 expenditure of less power than is ordinarily necessary.

20 A further object of this invention is the provision of an improved pumping jack which embodies a folding feature by which the jack may be folded into an out of the 25 way relation with respect to the pumping line or rod, so that access to the latter may readily be had either for the purpose of drawing the pumping rod, or working about the same.

Other objects and advantages of this invention will be apparent during the course 30 of the following detailed description.

In the accompanying drawings, forming 35 a part of this specification, and wherein similar reference characters designate corresponding parts throughout the several views,

Figure 1 is a side elevation showing the manner in which the improved pumping 40 jack is used in connection with other pumping apparatus.

Figure 2 is a plan view of the improved 45 pumping jack and its associating pumping apparatus.

Figure 3 is a cross sectional view taken substantially on the line 3—3 of Figure 1.

Figure 4 is a cross sectional view taken substantially on the line 4—4 of Figure 1, and

45 Figures 5, 6 and 7 are perspective views showing details of the improved pumping jack.

Figure 8 is a cross sectional view taken on the line 8—8 of Figure 1.

50 Referring to the pumping apparatus, the letter A may generally designate the pump rod; B the main beam pivoted at one end upon a support C; D the improved pump-

ing jack connected for operation to the main beam B by means of a pitman E; the improved pumping jack D being operated by a power cable or rod F.

The support C on the upper end thereof is preferably provided with a rib 15 which is arcuate in cross section and over which the beam B rests; the beam B being provided in one end thereof with a recess 16 to receive the rib 15 for fulcruming the beam B. The pump rod A is connected in pivotal manner to the beam B, by means 17.

A base 18 is provided for the pumping jack D, which upwardly thereon is provided with a groove 19 for pivotally receiving the pumping jack D in fulcruming relation thereon.

The improved pumping jack D furthermore consists of the upright rocker construction 20; a fixed frame construction 21 extending to one side of the upright construction 20; a foldable frame construction 22 extending to the opposite side of the upright construction 20; and the counterbalance receptacle 24 supported by the fixed frame construction 21.

The upright rocker construction 20 preferably consists of the fulcrum block 25, which is provided with a fulcrum rib 26 extending therebelow adapted for pivotal reception in the fulcrum groove 19 of the base 18. The upright rocker construction 20 furthermore includes the side bars 27 and 28 which extend upwardly from the block 25, being connected to the latter by suitable bolts 29 and 30 which respectively connect the fixed and foldable frame constructions 21 and 22 to the upright 20. The upright bars 27 and 28 are connected at their upper ends by means of a bolt construction 31 which receives details of the fixed and foldable frame constructions 21 and 22, as will be subsequently described.

The fixed frame construction 21 which is supported by the upright construction 20 to one side of the latter, preferably consists of a laterally extending arm connected at right angles to the upright construction 20, and which arm consists of a pair of bars 33 and 34 with a block 35 clamped therebetween. The bars 33 and 34 are fixedly connected by the bolt 29 to the upright construction 20 at the lower end of the latter, and

transverse bolts 37 may be used for connecting the arms 33 and 34 and the block 35 in a fixed relation. Diagonal brace bars 40 and 41 are connected as by a bolt 42 at their lower ends adjacent the outer end of the arm bars 33 and 34; said diagonal brace bars 40 and 41 being connected at their upper ends to the bolt 31 above mentioned.

At the opposite side of the upright 20 the foldable frame construction 22 is connected, which consists of an arm construction pivotally connected at the lower end of the upright construction 20 to normally extend at right angles to the latter. This arm construction comprises a pair of bars 45 and 46 pivotally connected by the bolt 30 to the upright construction 20. At their outer ends the arms 45 and 46 support a pitman fulcrum block 48 by means of a bolt 49; this fulcrum block 48 in the upper surface thereof of having a recess 50 within which the lower end of the pitman E may rest. A diagonal brace construction is provided for the foldable frame construction 22 which consists of sectional side bars. Side bar sections 51 and 52 are pivotally connected to the bars 45 and 46 by means of the bolt 49 above mentioned, and brace sections 53 and 54 are pivotally connected to the bolt 31 at the top of the upright construction 20. The brace sections 51 and 52 are pivotally hinged to the sections 53 and 54 by means of a bolt 58; a spacing sleeve 59 being provided to separate the brace sections 51 and 53 from the brace sections 52 and 54. When the sections 51 to 54 inclusive are extended in aligning relation they provide a diagonal brace for supporting the bars 45 and 46 in a right angled relation with respect to the upright construction 20, and this places the pumping jack in an operating position so that the pitman E may rest upon the fulcrum block 48.

At the upper end of the upright construction 20, and between the bars 27 and 28 of said upright construction a stirrup block 60 may be pivotally supported by the bolt 31; said stirrup block having a transverse opening 61 therein for receiving the bolt 31, and having a second opening or passageway 62 therethrough adapted to receive a bolt for pivotal connection of the stirrup 63 to the block 60. The stirrup 63 is of course a part of the power line F.

The counterbalancing feature of this invention consists of the box or receptacle 24 which is supported by the arm portion of the fixed frame 21; the receptacle 24 being bolted to the block 35 by means of bolts 65. The receptacle is, of course, open, and may receive therein stone, cement, scrap iron, or any approved weighing material 67 which will counterbalance the weight of the pump rod or line.

Referring to the operation of this invention, during pumping, the parts are assem-

bled as illustrated in Figure 1 of the drawings. The pitman E at its lower end rests upon the fulcrum block 48, and at its upper end engages in a recess in the lower side of the main beam B at a point adjacent the pump rod A and on the opposite side of the pump rod A from the pivotal support of the beam B with respect to the standard C. The pumping jack D is fulcrumed upon the base 18 as above mentioned, and the folding frame construction 22 is extended so that the pitman E may rest upon the fulcrum block 48. The power line F is connected by means of the stirrup 63 to the upper end of the upright construction 20 and suitable weighing material is disposed in the receptacle 24 for counterbalancing the weight of the pump line A. The power line or cable F transmits the power for rocking of the pumping jack D, so that upon the upstroke of the frame 22 the pump rod A will be elevated through the connection of the pumping jack with the beam B. The power line F is, of course, connected to the pumping jack at one end and to a central power station at the other, as many wells can be pumped from one such central power station. Each well must have its own pumping jack and power line, but incident to the simplicity of the improved pumping jack the counterbalancing feature of this invention renders the pumping apparatus all the more practical as many more wells may be operated during the pumping action with a given amount of power by the use of this improved pumping jack. A very great improvement of the improved pumping jack D lies in the fact that it does away with the necessity of detaching bolts and other complicated parts of the pumping jack and other apparatus in order that the pitman E may be disconnected from the pumping jack frame portion 22, and the latter may be swung back upon the fixed frame construction 21 in the manner illustrated by the dot and dash lines in Figure 1 of the drawings. In this position the pumping jack is entirely out of the way of the pumping rod or line A, so that workmen may with facility work about the pumping rod, or may draw the same without interference. While during operation the bolts 30, 31, 49 and 58 are tightened, they may be loosened to permit the pivotal folding action of the parts of the frame construction 22.

Various changes in the shape, size, and arrangement of parts may be made to the form of the improved pumping jack and apparatus herein shown and described, without departing from the spirit of this invention or scope of the claims.

I claim:

1. In a device of the class described a pivot member, a rigid frame extending to one side of the pivot member, and a collapsible frame extending to the opposite side of

- the pivot member which when in extended position is rigid with said rigid frame.
2. A pumping jack comprising an upright member, a rigid frame extending to one side of the upright member, a pivoted arm extending to the opposite side of said upright, and collapsible means for holding the arm in extended relation with respect to the upright member.
3. In a pump jack the combination of an upright construction, means rockably supporting the upright construction, a rigid frame extending to one side of the upright construction, and a collapsible frame extending to the opposite side of the upright construction adapted to be extended outwardly of the upright construction or collapsed with respect thereto.
4. A pumping jack comprising a base, an upright rockably supported on the base, a rigid frame extending to one side of the upright, an arm pivotally carried at the opposite side of the upright, and a collapsible brace adapted to support the pivoted arm in an extended relation with respect to the upright.
5. In a pumping jack the combination of an upright, an arm extending to one side of said upright, a brace connected at the outer end of said arm and to the upper end of said upright for stably holding the arm in extended relation with the upright, an arm pivotally connected to the opposite side of the upright with respect to the mounting of said first mentioned arm with the upright, and a collapsible brace connected at the outer end of the second mentioned arm and at the upper end of the upright adapted to be collapsed to permit folding of the second mentioned arm towards the upright.
6. A pumping jack comprising an upright construction, a pivot block carried at the lower end of said upright construction, a stirrup block carried at the upper end of said upright construction, a rigid frame extending to one side of the upright construction, an arm pivotally connected to the lower end of the upright and extending to the opposite side of the upright with respect to the rigid frame, a pitman support member carried by the free end of said arm, and a collapsible sectional brace connecting the free end of said arm to the upper end of said upright whereby the arm may be extended with respect to the upright or folded thereagainst.
7. In combination a base, an upright member, a rigid frame construction extending to one side of the upright member, a foldable frame construction extending to the opposite side of said upright, and means for connecting a power line to the upper end of said upright.
8. A pumping jack comprising a base, a block pivotally mounted on the base, a pair of bars connected at opposite sides of said block in a fixed relation therewith, a stirrup connecting block pivotally supported at the upper end of said bars therebetween, an arm connected at the lower end of said bars and extending to one side of the pivot axle thereof, a diagonal brace connected at the outer end of said arm and at the upper end of said bars, an arm extending to the opposite side of said bars in a pivotal connection therewith, and a diagonal brace consisting of a plurality of pivotally connected sections pivotally connected at the upper end of said bars and at the outer end of said last mentioned arm.
9. In combination a platform, a support carried by the platform, a beam pivoted at an end thereof on said support, a pump rod pivotally connected with said beam remote from said beam pivot, a pump jack structure pivoted intermediate its ends including a counterweight to one side of the pivot axis thereof and an arm extending to the opposite side of the pivot axis thereof, and a pitman connected between said arm of the jack and the beam pivot engaging said beam at a point thereon to the opposite side of said pump rod pivot with respect to the beam pivot on said support.
10. In combination a platform, an upright on the platform, a beam pivoted on said upright, a pump rod pivotally connected with said beam remote from the beam pivot on said upright and intermediate the ends of said beam, a second support, a pump jack structure pivoted intermediate its ends on said second support including a counterweight extending to one side of the pivot axis of said pump jack and a collapsible arm extending to the opposite side of the axis of said jack whereby the arm when extended projects toward said pump rod and when collapsed folds away from the pump rod toward said counterweight, and a pitman disposed between the collapsible arm of said jack and said beam engaging the latter at the opposite side of the pump rod pivot connection therewith with respect to the pivot action of the beam on said first mentioned support.
11. In combination a base, an upright member on the base, a counterweight rigid with the upright member extending to one side thereof, a foldable frame construction extending to the opposite side of said upright, and means for connecting a power line to said upright.
12. In combination a base, a movably mounted upright member, a frame construction carried by and rigidly extending to one side of the upright member, a foldable frame construction carried by and extending to the opposite side of said upright, and a counterweight carried by said rigid frame construction.

13. In an article of manufacture a pump jack comprising an upright pivot member, an arm pivotally connected with the upright pivot member and extended laterally there-
5 from at the lower end of said upright mem-
ber, and a sectional diagonal brace including
a plurality of pivotally connected sections

and at the ends thereof being pivotally con-
nected to the upper end of said upright, and
the outer end of said pivoted arm whereby 10
when the brace is extended in rigid relation
the arm will be extended from the upright
in rigid right angled relation.

JOHN D. BROWN.
